UNITED STATES PATENT OFFICE.

HARRY B. GARMAN, OF DETROIT, MICHIGAN, ASSIGNOR TO CHARLES E. THOMPSON,
OF CLEVELAND, OHIO.

DRIVING MECHANISM.

1,389,042.

Specification of Letters Patent. Patented Aug. 30, 1921.

Application filed June 7, 1919. Serial No. 302,379.

To all whom it may concern:

Be it known that I, HARRY B. GARMAN, a citizen of the United States, resident of Detroit, county of Wayne, and State of Michigan, have invented new and useful Improvements in Driving Mechanism, of which the following is a specification, the principle of the invention being herein explained and the best mode in which I have contemplated applying that principle, so as to distinguish it from other inventions.

My invention relates to driving mechanism and particularly to devices of that character designed for use upon passenger automobiles and automobile trucks. The design is intended to accomplish, in a more economical and satisfactory manner, the results set up in U. S. Letters Patent No. 1,349,197 upon universal joints, issued to myself and David V. Buck. In many respects the construction herein shown and described is similar to that set up in said U. S. Letters Patent No. 1,349,197. The particular differences as between the two inventions will be hereinafter set up in detail. However, the most important difference between these two inventions consists in reversing the standard spline provided automatically for adjusting the center distance when under load. For illustration, the standard spline shown and described in said U. S. Letters Patent consists of a propeller shaft sleeve provided with an exterior spline and serving as the male member, coöperating with a shell member provided with an interior spline and adapted to be integrally secured to the transmission and serving as the female member. My improved construction, herein shown and described and hereinafter claimed, consists in providing a hollow propeller shaft which is butt welded to a shell member having an internal spline and serving as the female member, adapted to coöperate with an external spline member secured to transmission elements such as the change-gear set and serving as the male member. Particular advantages of this construction will be hereinafter set up in detail.

The annexed drawings and the following description set forth in detail certain means embodying my invention, the disclosed means, however, constituting but one of the various mechanical forms in which the principle of the invention may be employed.

In said annexed drawings:

Figure 1 represents a plan view of my improved driving mechanism, the housing therefor being shown in section;

Fig. 2 represents a horizontal longitudinal section taken in the plane indicated by the lines II—II, Fig. 4;

Fig. 3 represents a partial longitudinal section and a partial elevation taken in planes at right angles to the elevation taken in Fig. 1;

Fig. 4 represents a transverse vertical section taken in the plane indicated by the lines IV—IV, Fig. 1; and

Fig. 5 represents a vertical transverse section taken in the plane indicated by the line V—V, Fig. 3.

Referring to the annexed drawings, a hollow propeller shaft is indicated by the ordinary 1 which is butt welded at its inner end to one end of a sleeve member 2 formed upon its inner surface with a spline element forming a female member and adapted to coöperate with the projecting end 3 of a male member welded to a joint element 4 and provided at that end with an exterior spline element. The sleeve 2 extends, as shown, to the outer end of the joint element 4. The hollow propeller shaft 1 is formed with a button 1' acting as a stop for the grease furnished to the spline members 2 and 3, this button 1' being fastened by a bur caused by the flash when welding shaft 1 to member 2. The abutting ends of the elements 2 and 3 are surrounded by a housing member 5 formed at one end with an internally threaded ferrule or nut member 6 adapted to coöperate with an externally threaded portion of the element 4, said sleeve 5 being formed with stuffing box 7 at its other end. Said nut portion 6 is grooved to receive and securely hold a member 8 of the housing which will be hereinafter more fully described. The sleeve member 5 is locked in place by means of a lock wire 9 secured in the nut member 6. Suitable elongated holes 10 are formed in the member 4, as plainly shown in Fig. 2, for allowing grease to work into the spline elements 2 and 3.

As was also true in said U. S. Letters Patent No. 1,349,197, the joint element 4 which is adapted to be secured to the propeller shaft end of the joint is of a reduced

cross-section forming a tongue 11 of the shape plainly shown in Figs. 2 and 3. The whole element 4 is a drop forging which is machined, also heat treated, and ground on 5 both sides. Adjacently the inner end of the reduced cross-section 11 of the joint element 4 is formed a clearance area indicated by the ordinal 12, for a purpose hereinafter mentioned and also fully described in said 10 U. S. Letters Patent No. 1,349,197. Said reduced end portion 11 is formed at its outer end with a comparatively small protuberance 13 which is internally threaded to receive a threaded bolt 14, for a purpose hereinafter fully described. The adjacent portion of the element 11 is also internally threaded to receive and hold said bolt 14. A cotter pin 14' passed through said protuberance 13 intersects the bolt 14 to retain 15 the latter in place. The elements of the joint adapted to be secured to the change-gear side are indicated by the ordinal 15, there being a pair of said elements, oppositely disposed, of the shape plainly shown 20 in Figs. 1 and 2, and formed with a common annular flange 16. The interior oppositely disposed faces 17 of said joint elements 15 are bearing surfaces and are adapted to co-operate with journal members hereinafter 25 fully described. These members 15 are drop forgings and the bearing surfaces 17 are machined at right angles to the diameter of the flange 16. The flange 16 is provided with cap screw holes 18 whereby the same 30 may be secured to the flange of the driving hub 19 of the transmission member 20.

The elements of my joint disposed intermediately the propeller shaft element 4 and the transmission elements 15 comprise a 35 pair of members 21 formed with end shoulders 22 disposed exteriorly of and abutting the side faces of the members 15, 15, respectively. The members 21 are thus held to position by the members 15, respectively. 40 These members 21 are machined all over, heat treated and ground. This construction is also similar to that shown in said U. S. Letters Patent. The exterior faces of the members 21 are journal surfaces co-operating 45 with the bearing surfaces 17 of the members 15 and the interior faces of the members 21 are plane surfaces adapted freely to slide relatively to the side faces of the extended end portion 11 and to co-operate therewith. The range of movement 50 of the extended end portion 11 relatively to the interior opposing faces of the members 21 is approximately one hundred and eighty degrees (180°) and the range 55 of movement of the journal surfaces of the members 21 relatively to the bearing surfaces 17 of the members 15 is sufficient for all practical purposes and is allowed for and the amount of which indicated, by the

clearance area 12. This last mentioned range 65 of movements is similar to that disclosed in said U. S. Letters Patent wherein the range is indicated by special Fig. 5. The members 21 and the extended end portion 11 are secured together by means of a pin 70 23 inserted through holes 24 formed in the members 15 and registering with slots 25 formed in the members 21. Said pin 23 is formed with a circumferential groove 26 disposed in such a plane and of such dimensions as to receive the externally threaded bolt 14 hereinbefore mentioned. By this means, the position of the pin 23 is fixed. This construction for thus securing the pin 23 differs from that shown in said U. S. 80 Letters Patent.

I provide a housing for the joint, the same consisting of the members 5 and 8 hereinbefore mentioned, secured at one end in the nut member 6, the member 8 being secured to and surrounding at its other end a third housing member 27, felt packing 28 being provided therebetween, as plainly shown in Figs. 1, 2 and 3. Said housing member 27 is formed with an annular 90 flange 29 adapted to be secured to the flange 16 of the joint elements 15 and to the transmission hub member 19 through the medium of suitable cap screws and the holes 18, hereinbefore mentioned. A tapped hole 95 in the housing provided with a pipe plug allows for the insertion of lubricant, as plainly indicated in Fig. 3, and suitable oil holes and grooves are suggested in the several figures, among which are holes 10 100 specifically hereinbefore mentioned.

As a result of reversing the spline in the manner herein shown and described and hereinafter claimed, I am enabled to greatly increase the cross-sectional area of the hollow shaft 1, thereby providing the maximum surface for withstanding torsional strain, in proportion to the weight of metal used, and at the same time efficiently weld the hollow driving shaft to the auxiliary 110 sleeve 2. This design also provides a satisfactory shaft of this character without the necessity of case hardening the parts. Thus, the design adds greatly to the strength of the construction as well as reducing the first 115 cost.

What I claim is:

1. In driving mechanism, the combination of a hollow driving shaft; a sleeve welded at one end to the inner end of said shaft, and formed with interior splines; a driven shaft; a co-operating universal joint disposed between said shafts; and external splines disposed upon the joint side of the mechanism and co-operating with said first-mentioned splines to form centering means for said joint and driving shaft, said sleeve 120 extending to the outer end of said joint, 125

2. In driving mechanism, the combination with a hollow propeller shaft and transmission means such as the change-gear set; of a sleeve forming a continuation 5 of said shaft and butt-welded to the inner end of said shaft; and centering means disposed intermediately of said shaft and set,

said means comprising internal splines formed in said sleeve and a member secured to said set and formed with coöperating external splines. 10

Signed by me, this 17th day of May, 1919.

HARRY B. GARMAN.
